UNITED STATES PATENT OFFICE.

HENRY ARTHUR THOMPSON, OF MANCHESTER, ENGLAND.

ACTUATING SIGNALS ON AND COMMUNICATING WITH TRAINS.

1,327,411.

Specification of Letters Patent.

Patented Jan. 6, 1920.

Application filed August 23, 1916. Serial No. 116,427.

To all whom it may concern:

Be it known that I, HENRY ARTHUR THOMPSON, a subject of the King of Great Britain and Ireland, residing at 25 Derby Road, Withington, Manchester, in the county of Lancaster, England, have invented new and useful Improvements in Actuating Signals on and Communicating with Trains, of which the following is a specification.

10 My invention relates to railway inductive signaling and control and consists in improvements in or modifications of the invention particularly described and ascertained in my prior Patent No. 1,227,021 dated May 22nd, 1917. In said specification is set forth a method whereby signaling to or the control of trains may be effected inductively by the combined action of a sensitive polarized telegraph relay, a reed relay or timed relaying sounder, and a valve-controlling magnet.

According to the present invention it is proposed to confine the signaling and control to localities within the danger or signaling zone.

25 For this purpose means are provided for transferring the control of the valve-controlling magnet from the reed relay to a timed relaying sounder. An illustration thereof is found in Figure 1 of the accompanying drawings. An alternative method, shown in Fig. 2, is to subdue the audible clear signal outside the signaling zone. Fig. 3 is illustrative of the wayside control.

30 In Fig. 1 X represents the sensitive pole-changing relay operated by the feeble induced currents, R' the reed relay, herein-after referred to as the silent relay, R² the relaying sounder, M the solenoid or valve controlling magnet, and C an automatic switch or cut-out device. When the train is outside the signaling zone a current is induced in the train coil A—by virtue of the latter's proximity to the pulsating magnetic field permanently maintained around the track conductor I, Fig. 3, which is fed with current at say 50 cycles from the generator G by way of the mains Q, the current being stepped down by a suitable resistance L', 35 reed R' vibrates, and the plunger P is retained within the solenoid coil, the danger indications thus being withheld. The coils of relay R' are so connected to the terminals of the pole-changing relay X and the divided battery that a current flows from battery terminal 1, via spring contact 2, automatic

switch contact piece 3, spring contact 4, relay terminal 5, relay terminal 6, pole-changing circuit closer 7, contact screw 8, to battery terminal 9; or from battery terminal 10, via contact screw 11, circuit closer 7, relay terminal 6, relay terminal 5, spring contact 4, contact-piece 3, and spring contact 2 to battery terminal 1. Thus when said circuit closer is oscillating to the alternations of the induced current reed R' vibrates and makes virtually continuous contact with flanking springs 12, 13, so that a current circulates from battery terminal 10, through switch terminals 14 and 15, solenoid terminals 16 and 17, flanking springs 12, 13, and reed R' to battery terminal 9; with the result that the plunger P is retained within the solenoid coil.

40 Upon the arrival of the train at a permanent break Y, Fig. 3, in the track magnetic field, situated at the entrance to the signaling zone Z, reed R' will come to rest, the induced current in the train coil A being intermittent. The solenoid circuit being thereby broken the spindle 18 attached to switch armature 19 falls, and the connection normally maintained through contact springs 2, 4, and switch contact-piece 3 (carried on the upper end of said spindle) is severed 45 and the continuity of the circuit containing the silent relay R' is interrupted, so that said relay can no longer control the solenoid. The further effect produced by the fall of the switch armature 19 (which is now out of range of the attractive force) is the joining up of the circuit containing the relaying sounder R², switch contact 3 resting upon spring contacts 20, 21. A current now flows from battery terminal 10 via contact screw 11, circuit closer 7, spring contact 21, switch contact 3, spring contact 20, and relay terminals 22, 23, to battery terminal 1; or from battery terminal 1 via relay terminals 23, 22, spring contact 20, contact 3, spring contact 21, circuit closer 7, and contact screw 8 to battery terminal 9. The control of the solenoid now being transferred to the relaying sounder a current circulates from battery terminal 10, through switch terminals 14, 15, solenoid terminals 16, 17, flanking springs 24, 25, and reed R² to battery terminal 9. The danger indications are still restrained and an audible clear signal announces a clear road through the danger zone, it being assumed that the semaphore S controlling the line wire W

is in the "proceed" position. The note will cease upon the armature 19 being replaced by the driver. The line wires L and W are separated from the rails by a sufficient space 5 so that no effective neutralizing current will be induced in the latter.

Provided that the rate of vibration is sufficiently high it is not essential for the production of a musical note that the sounding 10 attachments should be of resonant material. The object to be attained by the use of such material is simply an increase in the volume of sound. According to another method of attaining the result aimed at in this invention it is proposed to damp the reverberations of said attachments during the period in which the train is outside the danger zone. This result is obtained by attaching 15 a pad 26 (Fig. 2) of suitable material, such as rubber, to the cross-piece 27 fixed to the armature-carried spindle 28 of the electromagnet D, said pad normally pressing against the gongs 29 when the current in the solenoid circuit prevents the armature 30 of said electro-magnet from falling. When the train reaches the permanently inactive portion 25 of the track magnetic field the solenoid circuit will be momentarily broken and the coils 31, 32 being contained therein the armature 30 will be released and the volume 30 of sound greatly augmented. When the audible clear signal is no longer required the armature, now out of magnetic control, will be replaced by the driver.

35 Since it is not essential in my invention that the reed appertaining to the polarized reed relay or to the relaying sounder should vibrate between polar extensions having the same sign of polarity, the coils of such instruments may be mounted on extensions of dissimilar poles. The reversing current will pass through the coils in such direction and with such force that at a given moment only one such extension will be capable of attracting the armature. It is still essential, 40 however, that the attractive force shall be applied near the fixed end of the reed in order that the reed may be capable of responding sufficiently to a frequency somewhat 45 higher than its own, and also that the torsional effect shall still be at a maximum near the fixed end of the reed in order to prevent nodular or other undesired vibration.

50 I declare that what I claim is—

1. In a railway inductive signaling or control system, a reed relay on the train, a source of energy on the train, connections between the reed relay and the train source, 55 a polarized pole-changing relay on the train, wayside means including a wayside source

of energy for actuating the polarized pole-changing relay and thereby controlling the vibration of the reed relay by means of current from the train source, a valve controlling magnet, an automatic switch, connections between the automatic switch, the reed relay and the magnet whereby during vibration of the reed relay under control of said wayside means the automatic switch completes a circuit so that current impulses from the train source are sent through the valve controlling magnet to restrain the control valve release, the automatic switch being adapted to open the circuit last-mentioned when the reed relay ceases to vibrate under the way side control, a relay sounder on the train, and connections between the relay sounder, the train source and the automatic switch whereby when the automatic switch opens the circuit through the reed relay the circuit through the relay sounder is closed.

2. In a railway inductive signaling or control system, a normally inoperative 85 valve-operating magnet, a tuned reed relay adapted to send current impulses through the valve-operating magnet, an automatic switch controlled by said reed relay, and a tuned sounder brought into action when said automatic switch is no longer under control.

3. In a railway inductive signaling or control system, a polarized pole-changing telegraph relay adapted to respond to induced alternating currents, a local circuit, a polarized reed relay controlled by said telegraph relay and sending current impulses through the local circuit, an automatic switch armature controlled by said current 95 impulses, a tuned polarized relaying sounder brought into action upon the fall of said armature, and a valve controlling solenoid receiving current impulses from said reed relay or relaying sounder.

4. In a railway inductive signaling or control system, a tuned reed relay, means for vibrating the reed thereof, a tuned relaying sounder, train carried means for breaking the circuit through said reed relay and automatically making the circuit through 100 said sounder, a valve-controlling solenoid, and circuits controlled by said relay or sounder for holding the solenoid plunger.

In testimony whereof I have signed my 115 name to this specification in the presence of two subscribing witnesses.

HENRY ARTHUR THOMPSON.
